(57) **ABSTRACT**

A new *Verbena* plant particularly distinguished by pink
flowers with darker eyes, and a compact and upright growth
habit, is disclosed.

1

Genus and species: *Verbena~~x~~hybrida*.

Varietal denomination: 'KLEVP15622'.

BACKGROUND OF THE NEW PLANT

The present invention comprises a new and distinct variety of *Verbena*, botanically known as *Verbena~~x~~hybrida*, and hereinafter referred to by the variety name 'KLEVP15622'. 'KLEVP15622' originated from a cross-pollination conducted in September 2012 in Cobbitty, New South Wales, Australia between the proprietary female *Verbena* variety '60.00.12' (unpatented), and the proprietary male *Verbena* variety '75.00.12' (unpatented).

The seeds from the cross were sown and plants were grown for evaluation, where an individual plant designated 'KLEVP15622' was selected from the group of plants in Cobbitty, New South Wales, Australia in October 2013.

In October 2013, 'KLEVP15622' was first vegetatively propagated by vegetative stem cuttings in Cobbitty, New South Wales, Australia. 'KLEVP15622' was found to reproduce true to type in successive generations of asexual propagation via vegetative stem cuttings.

SUMMARY

The following are the most outstanding and distinguishing characteristics of this new variety when grown under normal horticultural practices in Cobbitty, New South Wales, Australia.

1. Pink flowers with darker eyes; and
2. A compact and upright growth habit.

DESCRIPTION OF THE PHOTOGRAPH

This new *Verbena* plant is illustrated by the accompanying photograph which shows the plant's overall plant habit including form, foliage, and flowers. The photograph is of a 16-week-old plant grown in a greenhouse in Stuttgart,

2

Germany in August 2014. The colors shown are as true as can be reasonably obtained by conventional photographic procedures.

5 DESCRIPTION OF THE NEW VARIETY

The following detailed descriptions set forth the distinctive characteristics of 'KLEVP15622'. The data which define these characteristics were collected from asexual 10 reproductions carried out in Cobbitty, New South Wales, Australia. Data was collected on three-month-old plants grown in a greenhouse in Cobbitty, New South Wales, Australia in June 2015 in Cobbitty, New South Wales, Australia. Color references are to The R.H.S. Colour Chart of The Royal Horticultural Society of London (R.H.S.) 2007.

Classification:

Family.—Verbenaceae.

Botanical.—*Verbena~~x~~hybrida*.

Common.—*Verbena*.

Designation.—'KLEVP15622'.

Parentage:

Female parent.—The proprietary female *verbena* variety '60.00.12' (unpatented).

Male parent.—The proprietary male *verbena* variety '75.00.12' (unpatented).

Plant:

Growth habit.—Compact and upright.

Height (from top of soil).—32.0 cm.

Width (horizontal plant diameter).—26.0 cm.

Time to produce a finished flowering plant.—Approximately 8 weeks.

Time to initiate and develop roots.—3 weeks.

Root description.—RHS 155B (White); fine and fibrous roots.

Stems:

Number of branches per plant.—More than 25.

Length.—21.0 cm.

Diameter.—0.25 cm.

Internode length.—Approximately 1.8 cm.
